DESIGN FOR A CIGARETTE PACKAGE HOLDER OR SIMILAR ARTICLE

Henry J. Tunstall, Rockledge, Pa.

Application February 15, 1947, Serial No. 136,926

Term of patent 14 years

(Cl. D85—2)

To all whom it may concern:

Be it known that I, Henry J. Tunstall, a citizen of the United States, residing at Rockledge, in the county of Montgomery and State of Pennsylvania, have invented a new, original, and ornamental Design for a Cigarette Package Holder or Similar Article, of which the following is a specification, reference being had to the accompanying drawing, forming part thereof, in which:

Fig. 2 is a top plan view thereof; and

Fig. 3 is a side elevational view thereof.

I claim:

The ornamental design for a cigarette package holder or similar article, as shown.

HENRY J. TUNSTALL.
